BATHING SUIT

Application filed May 28, 1930. Serial No. 455,824.

This invention relates to bathing suits and has for an object to provide a suit of the character with improved means embodying a flap at the posterior with closure therefore.

At the present time, bathing suits in use are provided with no posterior opening for sanitary purposes and access can only be had by dropping the entire suit. Unsuccessful experiments have been made with posterior openings and flaps, but such flaps have been secured by buttons or other similar fastenings. These buttons often come off and even when in place, are not capable of producing a fastening of sufficiently intimate holding ability not to expose the person of the wearer through the gaps between the buttons and along the sides of the legs.

It is an object of the present invention to provide such a garment with a posterior flap, which can be quickly and readily manipulated even when the garment is wet and which will hold the edges of the flap and garment in such intimate closed relation as to prevent exposure through any part of the slit.

A further object of the invention is to provide a bathing suit having a slit formed upon the sides of one leg portion and entirely across the back, at or adjacent to the waist line and down the opposite leg, with means for intimately closing the slit throughout its entire lineal extent.

A further object of the invention is to provide in a bathing suit a garment comprising a body garment and a nether garment, the latter being provided with an under part having a slit extending upwardly along one leg, across the back and down the opposite leg, with improved means for closing the slit and an outer part in the form of a skirt entirely covering the slit part.

According to the present invention, the bathing suit comprises a nether garment, approximately parallel slits formed upon the opposite sides of the garment extending upwardly to and across, at or adjacent to the waist line, such slits merging into a single slit forming a posterior flap.

This invention is directed to other objects and possesses other features of novelty and

advantage, some of which, together with the foregoing, will be hereinafter more fully set forth.

In the drawings:

Figure 1 is a view of a figure showing one side of a bathing garment, a part being broken away and exhibiting the position of the slit along the side of the leg,

Figure 2 is a posterior view of a fragment of the bathing suit with the slitted part disconnected and the flap depending,

Figure 3 is a posterior view of the garment with the flap secured in position, and

Figure 4 is an enlarged detail view of the flap fastening means.

The improved suit, which forms the subject matter of this application, will preferably comprise a body garment 10 and a nether garment 11. Externally of this part 11, a skirt part 12 may be employed, but such skirt part forms no part of the present invention.

The nether garment is provided with a slit 13 which extends entirely across the back of the garment at or adjacent to the waist line, and is curved at 14 to extend downwardly along the legs to an indeterminate position.

This slit 13 forms a flap 15, which at Figure 2 is shown dependent and at Figure 3 is shown in closed position. The slit forming the flap is closed by the use of a slide closure 16, sometimes commercially known as "Talon" type of closure or "zipper" type of closure, other names being applied thereto by different manufacturers.

These fasteners as found upon the market comprise metal hooks secured in interlocking portions along the edges of two relatively non-stretchable strips of fabric. The fabric strips here represented by the strip 16', are secured respectively along the cut edges, above noted, and prevent distortion of the elastic knitted fabric from

which bathing suits are almost universally constructed. It will be apparent from the drawings that the portion of the fastening organization which extends across the back lies normal to the back and that the portions which extend downwardly along the remote

sides of the legs lie normal to said remote sides which necessitates a spiraling intermediate said portions, specifically at the curves 100

14, as will be more clearly seen at Figure 3.

The closure 16 is opened and closed manually by a runner 17. When the runner is at the extreme end 18, the garment is entirely closed as shown at Figure 3, but when at the extreme end 19, the flap is disconnected as shown at Figure 3 and falls by gravity.

As will be seen from the drawings, but more specially from Figs. 1 and 3, the slide closure extends along and is normal to the remote sides of the legs and extends across and is normal to the back at substantially the waist line. This necessitates a curving and spiraling of the slide fastener strip.

15 Of course, the bathing suit herein illustrated, may be modified in various ways without departing from the invention herein set forth and hereinafter claimed.

The invention is hereby claimed as follows:—

1. A bathing suit comprising a nether garment having a slit formed entirely across the back and curved to continue downwardly along the remote sides of the legs forming a flap having rounded corners, strips of relatively non-stretchable material reinforcing the edges of the slit, and a sliding closure intimately connecting the margins of the flap and garment throughout the entire extent of the slit.

2. A bathing suit comprising a nether garment having a slit extending entirely across the back adjacent to the waist line and downwardly and anteriorly curved along the remote sides of the legs, and interlocking hooks carried by the margins of the slit, said hooks being normal to the posterior of the garment and both curving and spiraling to normal along the said remote sides of the legs.

40 In testimony whereof we have signed our names to this specification.

ALBERT FERRARI.
SIDNEY W. DEVERS.
